[57] CLAIM

The ornamental design for a cutting rod, as shown and described.

DESCRIPTION

FIG. 1 is a side elevation of a cutting rod according to my design;

FIG. 2 is a bottom view of the cutting rod as depicted in FIG. 1;

FIG. 3 is an inverted side view of the opposite side of the cutting rod shown in FIG. 1;

FIG. 4 is a view taken from the top of FIG. 1;

FIG. 5 is an end view of the left end of FIG. 1; and,

FIG. 6 is an enlarged sectional view taken on line 6—6 of FIG. 3.
